UNITED STATES PATENT OFFICE.

JOHN EDWARD GLOEKLER, OF PITTSBURGH, PENNSYLVANIA.

SHEET-METAL DRAIN-BOARD CONSTRUCTION.

Application filed December 10, 1926. Serial No. 153,820.

My invention consists of an improvement in drain boards for sinks and similar constructions. It has in view to provide a sheet metal board of strong, light construction, having a slightly inclined bottom, a rear upwardly extending splash board portion, and a relatively shallower front and end walls provided with rounded rims.

The board is particularly designed for attachment to and connection with a sheet metal sink construction forming the subject matter of a companion application filed herewith, Serial No. 153,819.

To such end, the board is formed of a main sheet metal blank having an upwardly bent splash board portion, a bottom portion at right angles thereto, and an upwardly bent front of less depth with a rounded edge portion, in one integral piece. Also, an upwardly extending end portion is welded to and merged into such portions, and various other features of construction and advantage, as more fully hereinafter described.

In the drawings, showing one preferred embodiment of the invention:

Fig. 1 is a perspective view of my improved splash board, as applied to a sink;

Fig. 2 is a view of the same in front elevation;

Fig. 3 is a longitudinal section on the line III—III of Fig. 1;

Fig. 4 is a cross section on the line IV—IV of Fig. 1;

Fig. 5 is a partial longitudinal section similar to Fig. 3, showing a modified construction of scouring ledge, used with a double unit sink.

The drain board, as a whole, in the form shown, is formed of a continuous sheet or blank of sheet metal bent to provide the rear wall 2, bottom 3, and front wall 4, the corner bends 5 being rounded, as shown, to provide a continuous integral construction.

Rear wall 2 is extended upwardly above the comparatively shallow front wall 4, to provide a protecting splash wall or back, of any desirable height. It is turned backwardly at the top by a square top flat section 7, and then downwardly parallel with the front sheet of rear wall 2, and is provided with similar end flanges 8, for finish at the outer end and connection at the inner end, respectively, as hereinafter described. Such back portion extends to any sufficient

height, and is preferably of the same height as that of the splash wall 6 of a sink, as like that of the companion application above noted.

The front wall 4 extends upwardly, integral with the bottom 3, and is rounded outwardly, as at 9, providing a finishing rim. Bottom 3 slopes upwardly, more or less, sufficient to provide drainage into the sink cavity and rim 9 preferably slopes to a slightly greater degree in the same direction, as shown in Fig. 2. The end portion of the drain board is closed by an end wall 10 extending inwardly between the end of the front wall 4 and the inner end portion of the splash wall 2. Said end is of a separate piece of sheet metal, having an upper rim 11 matching into the corner of rim 9 by a miter joint 12.

The lower edge of the end wall is rounded, as at 13, into the plane of the bottom 3, and is electrically welded thereto on the line α , thus providing a flush continuous surface on the inside. The inner end of the end wall is likewise welded to the lower end portion of the splash wall 2, as at 14, the end wall 10 being preferably cut out for interfitting connection therewith.

By such construction, it will be seen that the end wall forms a practically continuous extension of the bottom plate, with out any interruption, and is, in effect, integral therewith, due to its welded connection and any supplemental smoothing or finishing to remove roughness or obstruction.

At its inner end, bottom 3 is turned down over the inner edge portion of the adjacent rim 6 of the sink B, and is secured thereto by a plurality of screws or bolts 15 preferably having tightening nuts on the inner side. The splash board member 2 is similarly connected to the end portion of the splash wall 6 of the sink by bolts 16 fixedly connecting and supporting the back wall of the sink and providing, in effect, a continuous extension of the main sink splash wall 6 on the same general level therewith, clear out to the end of the drain board. The splash wall 6 of the sink is provided with an endmost web or flange 24 and splash wall 2 is similarly provided with a web or flange 25.

The joint 17 between the said two elements is substantially tight under the tension of

the bolts, preventing the entrance of any water, and the sheet metal of the back 2 of the drain board is extended across the joint and outwardly a slight distance by means of 5 the suitably shaped tongue extension 18, as in Fig. 1, immediately in the rear of the downwardly turned terminal lip of the bottom 3.

Rim 9 slopes downwardly toward such 10 juncture with the sink B and its rim b, and is provided with a terminal downwardly bent section 19, which fits neatly over the front rim of the sink, as in Fig. 2, forming, in effect, a slightly interrupted continuation 15 therewith.

The main drain board is rigidly supported outwardly from the sink by means of one or 20 more braces 20, fixedly connected with the supporting leg or legs of the sink at its inner lower portion, and with the outer end 25 of the drain board by flange and bolt connection, as at 21. In this manner, the drain board is rigidly supported, in addition to its connection with the back wall of the sink, so that it is, in effect, a relatively stable portion of it.

Where two or more sink units are associated, as in Fig. 5, the sinks B are preferably spaced more or less apart from each 30 other, and are connected by a scouring ledge 22, which fits over and around the usual rims b and is secured by bolts or screws 16 in the same general manner as is the inner edge of the drain board, Fig. 1.

35 The scouring ledge thus provides a covering bridge between the adjacent sinks, and also extends upwardly by a back 23 to the same general height as the sink bracket 6 at each side, being connected therewith by 40 flange and bolt connections 16, as already described.

The scouring ledge and its back are also provided with overlapping lips 18, similar 45 to that of the drain board, and as thus connected and mounted, the scouring ledge serves to provide a convenient and useful supporting floor between the sinks which are located somewhat apart from each other. The endmost sink, at one or both sides, is 50 preferably provided with a drain board, constructed, mounted and connected in the same general manner as already described.

It will be understood, also, of course, that 55 with either single or plural sinks, the drain board may extend to one or both sides, i. e., to the right or to the left of a single sink unit, or of the endmost portion of one or both sinks, where a plurality are associated.

The construction, utility and advantage of 60 the invention will be readily understood and appreciated by all those familiar with the manufacture and use of similar culinary elements. The manner of construction of the drain board provides continuous smooth surfaces, with rounded corners, and avoidance

of any sharp corners or pockets tending to collect foreign matter, or to interfere with cleansing of the surfaces.

Any projections or roughness along the 70 welded seam a may be ground off or otherwise removed, so as to render the interior surface smooth, after which it may be covered with any suitable coating material, as an enamel finish, or tin coating, or hot galvanized treatment. Due to the close joints 75 and continuity of surfaces, by reason of the joint connection with the sink itself, such treatment is rendered comparatively easy and successful, so that, when the drain board is associated and properly combined 80 with a sink, wash-tub, or similar vessel, the entire construction provides, in effect, a unitary equipment.

What I claim is:

1. In the construction of sheet metal drain 85 boards, a continuous blank forming a double-sided square top back, and a one piece bottom and front wall with the inner end of the bottom turned down for attachment to a sink rim, and an outer end wall having an 90 inwardly curved lower edge welded to and flushing with the bottom and welded to the back and front wall respectively.

2. In the construction of sheet metal drain 95 boards, a continuous blank forming a double-sided square top back, and a one piece bottom and front wall with the inner end of the bottom turned down for attachment to a sink rim, and an outer end wall having an 100 inwardly curved lower edge welded directly to and forming a flush extension of the bottom, bent upwardly and provided with an outwardly turned rim, and welded to the back and front wall respectively.

3. In the construction of sheet metal drain 105 boards, a continuous blank forming a back having outwardly turned top and end flanges, the end flange being adapted for connection with a similar end flange, the blank being bent forwardly to form a longitudinally sloping bottom inclined upwardly towards the outer end of the back and bent upwardly at the front to form a shallow sloping front wall having a front rounded rim, an outer end wall having an inwardly curved lower edge welded to the bottom, back and said front wall and its rim, an inner downwardly turned edge forming an attaching overlap connecting terminal for the bottom opposite the end wall, and a tongue extension of the back above said overlap terminal.

4. A sheet metal drain board formed of 115 a continuous blank having an upwardly extending back provided with a rearwardly extending connecting flange for attachment to a sink or the like, and having an inclined bottom bent forwardly at right angles thereto with a downwardly turned delivery terminal extending beyond said flange, an up- 120

wardly extending front wall having an outwardly turned rim sloping downwardly from its outer end towards said terminal, and having a projecting concave end for fitting over the rounded rim of a sink.

5. The combination with a sink having a rounded upper rim and a rear splash wall extension of sheet metal provided with a flanged end, of a drain board formed of 10 sheet metal having a rear splash wall extension provided with a flanged end, bolts connecting said flanged ends, an integral forwardly extending inclined bottom in front of the splash wall having a front sloping 15 wall and rounded at the top, a similar end wall having continuous welded connection with the splash wall, bottom and front wall, and a downwardly turned delivery end for the bottom lapping over and secured to the 20 rim of the sink.

6. The combination with a sink having a

rounded front upper rim and a rear splash wall extension of sheet metal provided with a flanged end, of a drain board formed of sheet metal having a rear splash wall extension provided with a flanged end, bolts connecting said flanged ends, an integral forwardly extending inclined bottom in front of the splash wall having a front wall rounded at the top and sloping downwardly 25 towards the rounded rim of the sink, a similar end wall having continuous welded connection with the splash wall, bottom, and front wall; a downwardly turned delivery end for the bottom lapping over and secured 30 to the rim of the sink, and a downwardly turned extension of the rounded top front wall of the drain board fitting upon the rounded rim of the sink.

In testimony whereof I hereunto affix my 40 signature.

JOHN EDWARD GLOEKLER.
